UNITED STATES PATENT OFFICE.

JEREMIAH E. LANGFORD, OF SALT LAKE CITY, UTAH.

RAILROAD-TIE AND RAIL-GRIP.

1,131,388.

Specification of Letters Patent. Patented Mar. 9, 1915.

Application filed June 20, 1914. Serial No. 246,266.

To all whom it may concern:

Be it known that I, JEREMIAH E. LANGFORD, of Salt Lake City, in the county of Salt Lake, and in the State of Utah, have invented a certain new and useful Improvement in Railroad-Ties and Rail-Grips, and do hereby declare that the following is a full, clear, and exact description thereof.

My invention relates particularly to ties 10 adapted to be used in railroads and provided with means for securing the rails thereto. It has special reference, however, to metallic ties and particularly steel ties designed for this purpose.

15 The object of my invention is to provide a railroad tie and rail grip which may be used on earth or gravel beds, in concrete constructions, on paved streets, on wooden wharves or trestles, as well as steel constructions such, for example, as bridges.

A further object of my invention is to provide a rail tie and gripping means which is adapted to hold the rails in place without the necessity of applying any railway spikes.

25 A further object of my invention is to provide a metallic railway tie which is so arranged as to effectively insulate the two rails from each other so as to avoid any interference with signaling devices which 30 are dependent upon the closing of an electric circuit between the two rails as, for example, through the wheels and axles of a car passing over the rails.

35 A further object of my invention is to provide a railroad tie of this kind which is exceedingly simple and which is, nevertheless, very strong in construction.

While my invention is capable of embodiment in many different forms, for the purpose of illustration I have shown only one 40 form thereof in the accompanying drawings, in which—

Figure 1 is a plan view of a railroad constructed in accordance with my invention; Fig. 2 is a cross-section of the same; Fig. 3 is a plan view of a rail and gripping means partly in section; Fig. 4 is an end elevation of the gripping means; and Fig. 5 is a cross-section of a tie with the rail in place.

50 In the drawings, I have shown a railroad tie 1 which is in the shape of a channel bar. That is to say, it is comprised of a base 2 and two lateral, upwardly directed flanges 3.

The base 2 is preferably provided with a 55 plurality of openings 4 to properly anchor

the tie to the roadbed. In the case of earth or gravel roadbeds, the earth or gravel passing through the openings 4 and resting upon the top of the base 2 will effectively anchor the tie in place. Where the tie is used upon 60 trestles or bridges, and where the tie is to be attached to longitudinal stringers, spikes or bolts may be passed through the opening 4 to attach the tie to the same. The flanges 3 have beveled ends 5 to prevent injury to 65 workmen when laying or repairing the railroad. As shown in Fig. 2 the tie 1 is arranged to support a plurality of rails 6 of the usual form in cross-section. Each of these rails 6 is supported in a pair of inner 70 grip plates 7 so arranged as to leave openings 8 between the grip plates 7 and the edges of the rail, so as to produce a wedging grip upon the base of the rail, when it is placed in position in the manner hereinafter 75 described. The inner grip plates 7 rest against plates or strips 9 of fiber or other electrically insulating material, and the strips or plates 9 in turn rest within outer grip plates 10. The outer grip plates 10 are 80 tapered so as to be thinner at one end than the other, so that they may act as wedges when being inserted in the ties to hold the rails in place. The outer grip plates 10 may be provided with recesses 11 to receive corresponding projections 12 on the inner grip plates 7, the upper ends of which grip plates 7 are bent over in such a manner as to cause the projections 12 to register with the recesses 11. One of the principal advantages 85 of turning the upper ends of the inner grip plates 7 over in the manner described is to prevent an accumulation of water on the base of the rail from establishing an electrical circuit between the inner grip plates 7 90 and the outer grip plates 10. Preferably the grip plates 7 and 10 and the insulating plates or strips 9 are cemented together with any suitable cement. The lateral flanges 3 on the ties have recesses or openings 13 provided therein to receive the rails 6 and the grip plates. Said openings 13 at their uppermost portions are substantially the width of the bases of the rails to be supported by the ties. Below the upper parts of these 100 openings 13, however, the openings are widened in such a manner as to receive the grip plates 7 and 10. If desired, as shown in Fig. 5, the openings 13 may be produced by cutting the sides of said opening and bend- 105 110

ing downwardly in the interior of the tie the portions 14, so cut out, until they rest against the base 2 of the tie. The presence of these turned down portions 14 tends to strengthen the ties. The openings 13 are, of course, made in such a way that the openings in one of the flanges 3 are a little wider than the openings in the other flange 3 in order to accommodate the tapering outer grip plates 10.

Railroads may be constructed primarily with ties of this character or they may be repaired by replacing other forms of ties with ties of this kind. Assuming that the railroad is being built with ties of this kind, the ties are placed at the proper intervals along the roadbed, and the rails are then dropped into place in the openings 13. The inner grip plates 7 and outer grip plates 10 and interposed strips of insulating material 9 which have been previously preferably attached together by means of cement, are now applied to the rails by insertion thereof between the edges of the bases of the rails and the wider portions of the recesses or openings 13, the thinner ends of the outer grip plates 10 being inserted first and the composite grip plates being then driven in place until the wedging action of the grip plates on the bases of the rails tightly clamps the rails in place. If the railroad is being laid along the ground or upon gravel, the roadbed is now filled with the earth or gravel up to the required level, and the ties are now securely held in place by this means. If, on the other hand, the railroad is being laid along a trestle or on a bridge, fastening means may be applied through the openings 4 to securely hold the ties in place. An accumulation of water along the bases of the rails 6 will not establish an electrical circuit between the inner grip plates 7 and the outer grip plates 10, owing to the position of the turned over ends of the inner grip plates 7. The two rails 6 will therefore be insulated from each other and signaling systems involving the completion of a circuit between the rails when the train passes, will not be interfered with.

While I have described my invention above in detail, I wish it to be understood that many changes may be made therein without departing from the spirit of my invention.

I claim:

1. In combination, a railroad tie having a recess to receive a rail and tapering clamping means at the side of the rail, comprising an inner and outer plate separated by an insulating plate.

2. In combination, a railroad tie having a recess to receive a rail and tapering clamping means at the side of the rail, comprising an inner and outer plate separated

by an insulating plate, the inner plate and insulating plate having their ends turned over the end of the outer plate.

3. In combination, a railroad tie having a recess to receive a rail and tapering 70 clamping means at the side of the rail, comprising an inner and outer plate separated by an insulating plate, the inner plate and insulating plate having their ends turned over the end of the outer plate into a recess in the outer plate.

4. In combination, a U-shaped railroad tie having a recess to receive a rail and tapering clamping means at the side of the rail, comprising an inner and outer plate 80 separated by an insulating plate.

5. In combination, a U-shaped railroad tie having a recess to receive a rail and tapering clamping means at the side of the rail, comprising an inner and outer plate 85 separated by an insulating plate, the inner plate and insulating plate having their ends turned over the end of the outer plate.

6. In combination, a U-shaped railroad tie having a recess to receive a rail and tapering 90 clamping means at the side of the rail, comprising an inner and outer plate separated by an insulating plate, the inner plate and insulating plate having their ends turned over the end of the outer plate into a recess in the outer plate.

7. In combination, a U-shaped railroad tie having a recess to receive a rail and tapering clamping means at the side of the rail, comprising an inner and outer plate 100 separated by an insulating plate, the material from the recess being bent downwardly to the base of the U-shaped tie.

8. In combination, a U-shaped railroad tie having a recess to receive a rail and 105 tapering clamping means at the side of the rail, comprising an inner and outer plate separated by an insulating plate, the inner plate and insulating plate having their ends turned over the end of the outer plate, the material from the recess being bent downwardly to the base of the U-shaped tie.

9. In combination, a U-shaped railroad tie having a recess to receive a rail and tapering clamping means at the side of the rail, comprising an inner and outer plate 115 separated by an insulating plate, the inner plate and insulating plate having their ends turned over the end of the outer plate into a recess in the outer plate, the material 120 from the recess being bent downwardly to the base of the U-shaped tie.

10. In combination, a railroad tie having a recess to receive a rail and tapering clamping means at the side of the rail, comprising an inner and outer plate separated by an insulating plate, said plates being 125 united with cement.

11. In combination, a railroad tie having a recess to receive a rail and tapering 130

clamping means at the side of the rail, comprising an inner and outer plate separated by an insulating plate, the inner plate and insulating plate having their ends turned over the end of the outer plate, said plates being united with cement.

12. In combination, a railroad tie having a recess to receive a rail, outside wedging plates for clamping the rail to the tie, in-

sulating plates inside of the same and inner gripping plates inside of the insulating plates.

In testimony that I claim the foregoing I have hereunto set my hand.

JEREMIAH E. LANGFORD.
